UNITED STATES PATENT OFFICE.

THEODORE BURR, OF HASTINGS, MICHIGAN, ASSIGNOR TO HIMSELF, J. B. LOBDELL,
A. PELHAM, AND H. BURR.

MACHINE FOR CUTTING FILES.

Specification of Letters Patent No. 27,591, dated March 20, 1860.

To all whom it may concern:

Be it known that I, THEODORE BURR, of the town of Hastings, in the county of Barry and State of Michigan, have invented 5 a new and useful Machine for Cutting Files; and I do hereby declare that the following is a full, clear, and exact description of the construction and operation of the same, reference being had to the annexed 10 drawings, making a part of this specification.

I construct a metallic bed-piece or frame work marked A upon the drawings, with ways for a slide or table marked B having 15 fasteners marked C by which the blank file is firmly secured to the table, and also with ways for a pedestal marked D, upon which I adjust the hammer and chisel cutters, and also the spring to bear upon the 20 hammer, the pedestal being so constructed as to receive a set screw marked E attached to the bed, by which means the force of the hammer is varied so as to cut the required depth in the file, by changing it more or less 25 in mesh with the tappets on the cylinder marked F, the cylinder being so constructed, as to contain various sets of tappets changing in number with a spring catch in the

end of the cylinder, can be moved or secured to any row of tappets desired, which 30 being brought in contact with the hammer governs the gage or cut in the file, which is moved steadily by means of a rack on the underside of the table meshing in a pinion upon a shaft, upon which is fixed a spur 35 wheel drawn by means of a screw marked G moved by face gearing from the driving shaft, until the cog or spur on the table comes in contact with a lever pinion which 40 raises the screw out of mesh and permits the table to be drawn back by means of a weight or spring.

I do not claim a hammer operated upon by a spring neither do I claim a slide moved by an endless screw.

What I claim as my invention, and desire to secure by Letters Patent is—

The use of the cylinder F constructed as described in connection with spring hammers, cutters, and file blank carriers, the 50 whole operating in the manner, and for the purpose described.

THEODORE BURR.
